UNITED STATES PATENT OFFICE.

LOUIS BLOCK, OF NEW YORK, N. Y., ASSIGNOR TO LEAH ELIZABETH BLOCK, OF NEW YORK, N. Y.

EARPIECE-DISINFECTOR.

1,027,174.

Specification of Letters Patent.

Patented May 21, 1912.

Application filed March 13, 1912. Serial No. 683,633.

To all whom it may concern:

Be it known that I, LOUIS BLOCK, a citizen of the United States, and a resident of New York city, county and State of New York, have invented a certain new and useful Improvement in Earpiece-Disinfectors, of which the following is a specification.

This invention relates to means for dis-
10 infecting the ear-pieces of telephone re-
ceivers and the like, the object of the in-
vention being to provide a simple and
efficient means for the purposes indicated.

My invention may be utilized in connec-
15 tion with such ear-pieces without varying
the outward appearance or size of the ear-
piece, and without offering anything visible
to users of the receiver. The ear-piece, as
usually constructed, consists of a hard rub-
20 ber cap which screws upon the end of the
magnet-holder and over the diaphragm,
and is provided with an opening and a bell-
shaped cavity or sound-amplifier. In the
practice of my invention, I retain all these
25 peculiarities, while providing for the use
of the disinfectant.

In the accompanying drawing, forming
part of this specification, the reference let-
ter *a* marks a hard rubber cap which is
30 provided with screw-threads *b* whereby it
screws on the end of the magnet-holder and
is also provided with an opening *c* for the

purpose of exposing the diaphragm (not
shown).

d marks the circular collar surrounding 35
the bell-mouth, and I provide this collar
with a groove *e*, fill the said groove with
wicking or felt or other porous material *f*,
and screw on a cap *g* which has an internal
flange *h* for covering the material *f* and 40
also forming a prolongation of the bell-
mouth. When the cap *g* is screwed down
hard, there is left a narrow slit *i* between
the flange *h* and the outer face of the collar
d, whereby a passageway is provided for 45
the escape of disinfectant into the bell-
mouth, whence it spreads into the dia-
phragm chamber of the receiver and well
as outwardly, thus disinfecting not only
the instrument but also the ear of the user, 50
and so preventing the spread of disease.

What I claim is—

In the ear-piece of a receiver, a grooved
collar for holding disinfectant, and a screw
cap covering said collar and groove and 55
leaving an adjustable opening for the pas-
sage of disinfectant.

Signed at New York city, in the county
of New York and State New York, this 8th
day of March, A. D. 1912.

LOUIS BLOCK.
